UNITED STATES PATENT OFFICE.

EMIL A. SCHUELKE AND JULIUS ROSS, OF MERIDEN, CONNECTICUT, ASSIGNEES TO THE NAPIER CO., OF MERIDEN, CONNECTICUT, A CORPORATION.

VANITY BOX.

Application filed July 13, 1927. Serial No. 205,367.

This invention relates to improvement in vanity boxes, the object being to provide a box of attractive appearance and sufficiently strong to withstand ordinary wear and tear, but formed from comparatively thin metal, so as to be less cumbersome to carry about, and with beveled edges, so as not to wear the lining of handbags in which they are commonly carried, and to be conveniently arranged so as to expose the various articles contained therein, and the invention consists in the construction as hereinafter described and particularly recited in the claims.

In the accompanying drawings:

Fig. 1 is a face view of a vanity box constructed in accordance with our invention;

Fig. 2 is a side view of the same, showing it open in broken lines;

Fig. 3 is a sectional view on the line 3—3 of Fig. 1, enlarged;

Fig. 4 is a sectional view on the line 4—4 of Fig. 3;

Fig. 5 is a sectional view on the line 5—5 of Fig. 3;

Fig. 6 is a sectional view on the line 6—6 of Fig. 2;

Fig. 7 is a perspective view of the box-frame, detached; and

Fig. 8 is a perspective view of the partition-frame, detached.

In carrying out our invention, we employ what, for convenience, we will term a box 10 and cover 11. These are formed at one end

35 with knuckles 12 and 13, through which a pin 14 extends, so as to hinge the cover to the box, and a spring 31 may be provided, tending to separate the box and cover. Preferably, the edges of the box and cover

40 will be beveled to add to the attractiveness of the device. Hinged to the outer end of the cover is a cap 15. In the bottom of the box is a mirror 16 held in place by a sheet-metal bezel 17 which closely fits the box, so as to hold the mirror therein. In the box

45 10 is a frame 18, slightly deeper than the box, so as to project slightly beyond the edge of the box and over which edge the edge of the cover extends, so as to form a tight joint. The forward end 19 of the frame also projects beyond the forward end of the box, so as to form a seat for the edge of the cap 15, which is provided with a slight finger 20 to enter a notch 21 formed 50 for it in the bottom of the frame, whereby

the cap will be held in its locked position. Set into the frame is a rectangular partition 22 to form a compartment for a rouge compact, and one edge of this partition is formed with a lip 23, serving to hold the compact in place, and with lips 24 and 25 which extend into the forward end of the box and beneath which powder and a powder-puff may be held. These lips 24 and 25 coact with the inward projection 26 at the other end of the frame 18. Pivotedly mounted in the cap 15 is a lip-stick holder 27 adapted to receive a lip-stick 28, and secured to the cap is a spring 29, the tendency of which is to force the free end of the lip-stick holder outward. A spring 30 may be provided to throw the cap in its open position, if desired.

With the cover closed against the box and the two interlocked by the cap, the device 75 comprises a neat appearance, as all joints are tight. To open the box, the cap is disengaged from the box by a slight pressure on the box itself, which allows the box to be turned away from the cover under the 80 action of the spring 31, thus making the opening operation practically automatic. This leaves the mirror exposed, and the rouge compact and powder are in convenient position for use. At the same time, the 85 lip-stick holder will be moved out of the cap in a convenient position, so that the lip-stick may be removed therefrom.

By providing the box with a frame and partition, reinforcement of the box is 90 secured, and while formed of very light material, together form a structure of sufficient strength but light in weight.

We claim:

1. A vanity box, comprising a box and a 95 cover hinged together, a cap hinged to the cover, a frame mounted in the box and projecting slightly beyond the edges thereof, forming a bearing for the cover and cap, and a partition in said frame, said partition 100 formed with projecting lips.

2. A vanity box, comprising a box and a cover hinged together at one end, a cap hinged to the opposite end of the cover, a frame located in the box and projecting 105 slightly beyond the end of the box and having its edges projecting slightly beyond the edges of the box, forming a seat for the cover, means for interlocking the cap with the frame, a partition set into said frame and 110

formed with retaining-lips, and a lip-stick holder pivotally mounted in the cap.

3. A vanity box, comprising a box and a cover hinged together at one end, a cap 5 hinged to the opposite end of the cover, a frame located in the box and projecting slightly beyond the end of the box and having its edges projecting slightly beyond the edges of the box, forming a seat for the 10 cover, means for interlocking the cap with the frame, a partition set into said frame and formed with retaining-lips, a lip-stick holder pivotally mounted in the cap, and a spring 15 tending to throw the free end of the lip-stick holder outward.

4. A vanity box, comprising a box and a cover, the box and cover hinged together, a cap hinged to the cover, the box, cover and cap formed with beveled edges, a frame in

said box and closely fitting therein and 20 formed with beveled surfaces closely fitting the bevel in the box, the edges of the frame projecting beyond the edges of the box, forming a seat for the cover, the end of the frame projecting beyond the end of the box, 25 forming a seat for the cap, means for interlocking the cap therewith, a rectangular partition located at the hinged end of the frame and formed with retaining-lips projecting from the upper edges, a lip-stick 30 holder pivotally connected at one end in said cap, and a spring mounted in the cap and tending to force the free end of the lip-stick holder outward.

In testimony whereof, we have signed this 35 specification.
